United States Patent

Des. 241,789
Patented Oct. 12, 1976

241,789

KEY-RING HOLDER

Roger S. Reiss, 260 Waverly Ave.,
Newton, Mass. 02158

Filed Apr. 2, 1975, Ser. No. 564,455

Term of patent 14 years

Int. Cl. D2—07

U.S. Cl. D2—400

FIG. 1

FIG. 2

FIG. 3

FIG. 4

FIG. 1 is a front perspective view of a key-ring holder showing my new design;

FIG. 2 is a right side elevational view thereof, the left side being a mirror image thereto;

FIG. 3 is a right rear elevational view thereof; and

FIG. 4 is a top plan view thereof.

I claim:

The ornamental design for a key-ring holder, substantially as shown and described.
